[57] **CLAIM**

The ornamental design for a passive infrared intrusion detector unit, as shown.

DESCRIPTION

FIG. 1 is a perspective view of a passive infrared intrusion detector unit showing our new design;

FIG. 2 is a top plan view thereof;

FIG. 3 is a back elevational view thereof;

FIG. 4 is a side elevational view thereof; and

FIG. 5 is a front elevational view thereof.

FIG. 1

FIG. 2

FIG. 3

FIG. 4

FIG. 5
